UNITED STATES PATENT OFFICE.

JAMES ROBINSON AND PERCY ROBINSON, OF LEEDS, ENGLAND.

ANCHOR USED IN CONNECTION WITH MECHANICALLY-OPERATED FARM IMPLEMENTS
WORKING ON THE FIXED-CABLE SYSTEM.

Application filed August 31, 1922. Serial No. 585,560.

To all whom it may concern:

Be it known that we, JAMES ROBINSON and PERCY ROBINSON, British subjects, residing at Leeds, in the county of York, 5 England, have invented certain new and useful Improvements in Anchors Used in Connection with Mechanically-Operated Farm Implements Working on the Fixed-Cable System, of which the following is a 10 specification.

In mechanically operated farm implements of the kind wherein the implement is provided with a motor by which it is made to haul itself along a fixed cable stretched 15 between two anchors situated on opposite headlands, the means hitherto proposed for moving these anchors ahead at each bout of the implement have not proved successful in practice; and the object of this present invention is so to construct and operate 20 said anchors as to enable them to be moved ahead automatically in a simple and efficient manner while at the same time providing for a better anchorage at the conclusion 25 of each forward movement of said anchors.

According to our invention, each headland anchor is provided, in addition to the usual drag rope or other shifting gear, 30 with a transmission drum around which the end of the implement cable is wound instead of being attached to the main frame of the anchor as heretofore, and the said transmission drum is coupled to the shifting gear 35 and also to a rocking frame provided on the main frame and being fitted with one or more discs or tines so as to constitute an auxiliary anchor; the arrangement being such that on rotating the transmission drum by an outward 40 pull on the cable, the main anchor becomes automatically moved forward by the shifting gear and the auxiliary anchor carried thereby simultaneously rocked on its pivot so as to bring its discs or tines down 45 into the ground and thus ensure a better anchorage at the conclusion of such forward movement.

In this way, the cable along which the implement travels is utilized not only to 50 impart the desired forward movement of the main anchor but also to bring into the anchoring position the auxiliary anchor whose rocking movement determines the extent of forward movement of the said main 55 anchor; and it will be seen that as the force

exerted on the auxiliary anchor will be in proportion to the pull or strain on the cable, the greater the power required to move the implement through the soil the greater becomes the holding power of the anchor 60 as a whole.

The pull on the cable to effect the forward movement of the main anchor and the rocking of the auxiliary anchor into the anchoring position as above described is 65 due to the drag of the implement, which drag on being released allows a counterbalance weight provided on the auxiliary anchor to rock the latter on its pivot back into the normal or inoperative position and 70 through such movement cause the transmission drum to be rotated in the reverse direction and rewind thereon sufficient of the cable to permit of the subsequent forward movement of the main anchor and the bringing 75 of the auxiliary anchor again into the anchoring position.

In order that the invention may be clearly understood, we will proceed to describe the same with reference to the example of 80 construction shown in the accompanying drawings; wherein:

Figs. 1, 2 and 3 are respectively a side elevation, a sectional end elevation and a plan view of a headland anchor for use in connection with farm implements working on the fixed cable system constructed in accordance 85 with our invention.

Referring to the drawings, 1 is the main frame of the anchor having running wheels 90 2 formed with discs 2^x which sink into the ground 3, while 4 is a stud having loosely mounted thereon a winding drum 5 carrying a drag rope 6 whose forward or outer end is secured to the ground 3 by a claw or other 95 fixing (not shown); all of which are of known or ordinary construction.

According to our invention, the main frame 1 is fitted with a framing 7 which carries a vertical shaft 8 on which is keyed a 100 transmission drum 9 around which the end of the implement cable 10 is wound, and the said transmission drum 9 is coupled to the winding drum 5 through an intermediate one-way clutch 11, spur pinion 12 and attached spur wheel 13, while the shaft 8 of the transmission drum 9 is coupled to a rocking frame 14, pivoted at 15 to the framing 7, through a pair of intermediate bevel wheels 16, shaft 17, spur pinion 18 and at- 110

tached spur segment 19. The rocking frame 14 carries at its forward end a disc 20 and is provided at its rear end with a counter-balance weight 21, so as to constitute an auxiliary anchor; and the spur wheel 13 of the winding drum 5 is fitted with a spring-actuated pawl 22 adapted to prevent the backward rotation of the said drum 5, while the main frame 1 carries a spring 23 with which 10 the rocking frame 14 engages when brought into the active position where it is steadied by a guide rail 24 situated on the said frame 1.

In use, the action of the anchor is as follows:—

As the implement travels away from the anchor, the latter remains inoperative owing to the fact that no strain whatever comes upon the cable 10; while on the implement 20 commencing the return bout, the strain put upon the cable 10 by the drag of the implement has the effect of unwinding a few coils of the said cable 10 from off the transmission drum 9 by which the latter is rotated and 25 with it its shaft 8 which, through the medium of the clutch 11 and spur gearing 12, 13, simultaneously rotates the winding drum 5 so as to wind in the drag rope 6 and thus cause the anchor as a whole to advance. The rotation of the transmission drum 9 and its shaft 8 simultaneously, through the medium of the bevel wheels 16, shaft 17 and spur gearing 18, 19, has the effect of rocking the frame 14 on its pivot 15 so as to translate 30 it from the full line position into the dotted line position and bring the disc 20 of the said frame 14 down into the ground 3 (see Fig. 1), thus terminating the rotation of the transmission drum 9 and in consequence the 35 forward travel of the anchor as a whole. The anchor being locked in the anchored position, the implement now hauls itself along the cable 10 toward said anchor, and should any increased load be transmitted to the 40 cable 10 during the forward travel of the implement such extra strain will be transferred by the cable 10 to the anchor transmission drum 9 and its connected rocking frame 14, thus causing the disc 20 to sink 45 further into the ground 3 and so enable the anchor to withstand such extra side strain.

On the implement arriving at the anchor and the strain on the cable 10 having been released, the frame 14 is, through the medium 50 of its counter-balance weight 21 assisted by the spring 23, rocked on its pivot 15 back into the normal or inoperative position shown full lines at Fig. 1 and through such movement the transmission drum 9 is simultaneously 55 rotated in the reverse direction and rewinds thereon sufficient of the cable 10 to permit of the subsequent forward movement and anchorage of the anchor by repeating the operation above described.

60 It will be understood that the anchor on

the opposite headland will be operated in like manner to that of the anchor herein described, thus enabling the said anchors to be moved ahead and simultaneously anchored automatically at each bout of the implement merely through the pull of its cable 10.

What we claim as our invention and desire to secure by Letters Patent is:—

1. In a headland anchor for use in connection with mechanically operated farm implements working on the fixed cable system, the combination of an anchor frame mounted on running wheels, a shifting gear on the anchor frame, a cable-carrying transmission drum on the anchor frame coupled to the shifting gear, and a rocking frame pivoted on the anchor frame carrying tines and being coupled to the transmission drum whereby through the pull of the implement cable the transmission drum is directly rotated to cause the shifting gear to move the anchor ahead and the pivoted frame to be simultaneously rocked so as to bring its tines down into the ground and determine the extent of the forward movement of the anchor as a whole.

2. In a headland anchor for use in connection with mechanically operated farm implements working on the fixed cable system, the combination of an anchor frame mounted on running wheels, a shifting gear on the anchor frame, a cable-carrying transmission drum on the anchor frame coupled to the shifting gear through a one-way clutch, a rocking frame pivoted about centrally to the anchor frame carrying tines at one end thereof and being coupled by gearing to the transmission drum whereby through the pull of the implement cable the transmission drum is directly rotated to cause the shifting gear to move the anchor ahead and the pivoted frame to be simultaneously rocked so as to bring its tines down into the ground and determine the extent of the forward movement of the anchor, and a counter-balance weight at the other end of the pivoted frame adapted on the pull of the implement cable being released of rocking the said frame back into the normal or inoperative position and through such movement of simultaneously rotating the transmission drum in the opposite direction so as to rewind thereon sufficient of the cable to permit of the subsequent forward movement and anchorage of the anchor.

3. In a headland anchor for use in connection with mechanically operated farm implements working on the fixed cable system, the combination of an anchor frame mounted on running wheels formed with ground-engaging discs, a drag-rope shifting gear on the anchor frame, a cable-carrying transmission drum on the anchor frame coupled to the shifting gear through

a one-way clutch, a rocking frame pivoted about centrally to the anchor frame carrying tines at one end thereof and being coupled by gearing to the transmission 5 drum whereby through the pull of the implement cable the transmission drum is directly rotated to cause the shifting gear to move the anchor ahead and the pivoted frame to be simultaneously rocked 10 so as to bring its tines down into the ground and determine the extent of the forward movement of the anchor, and a counter-balance weight at the other end of the pivoted frame adapted on the pull of the implement 15 cable being released of rocking the said frame back into the normal or inoperative position and through such movement of simultaneously rotating the transmission drum in the opposite direction so as to rewind 20 thereon sufficient of the cable to permit of the subsequent forward movement and anchorage of the anchor.

4. In a headland anchor for use in connection with mechanically operated farm 25 implements working on the fixed cable system, the combination of an anchor frame mounted on running wheels formed with ground-engaging discs, a drag-rope shifting gear on the anchor frame, a cable-carrying 30 transmission drum on the anchor frame coupled to the shifting gear through inter-

mediate spur wheels and a one-way clutch, a rocking frame pivoted about centrally to the anchor frame carrying tines at one end thereof and being coupled by intermediate 35 bevel wheels and spur gearing to the transmission drum whereby through the pull of the implement cable the transmission drum is directly rotated to cause the shifting gear to move the anchor ahead and the pivoted 40 frame to be simultaneously rocked so as to bring its tines down into the ground and determine the extent of the forward movement of the anchor, and a counter-balance weight at the other end of the pivoted frame adapted 45 on the pull of the implement cable being released of rocking the said frame back into the normal or inoperative position and through such movement of simultaneously rotating the transmission drum in the opposite 50 direction so as to rewind thereon sufficient of the cable to permit of the subsequent forward movement and anchorage of the anchor.

In witness whereof we have hereunto set 55 our hands in the presence of two witnesses.
